(57) **CLAIM**

The ornamental design for an LED flashlight as shown and described.

DESCRIPTION

FIG. 1 is a bottom, front and left side perspective view of an LED flashlight showing my new design;
 FIG. 2 is a top, rear and right side perspective view of FIG. 1;

FIG. 3 is a front elevational view of FIG. 1;

FIG. 4 is a rear elevational view of FIG. 1;

FIG. 5 is a left side view of FIG. 1;

FIG. 6 is a right side view of FIG. 1;

FIG. 7 is a top plan view of FIG. 1;

FIG. 8 is a bottom plan view of FIG. 1; and,

FIG. 9 is an enlarged view of portion 9 in FIG. 1.

The evenly-spaced broken lines in the drawings illustrate portions of the LED flashlight which form no part of the claimed design. In FIGS. 1 and 9, the dash-dot-dash broken lines represent sectional designations that form no part thereof.
